UNITED STATES PATENT OFFICE

153,640

DESIGN FOR AN ASH TRAY

Adolph Schertz, Youngstown, Ohio

Application July 27, 1948, Serial No. 147,800

Term of patent 3½ years

(Cl. D85—2)

To all whom it may concern:

Be it known that I, Adolph Schertz, a citizen of the United States, residing at Youngstown, in the county of Mahoning and State of Ohio, have invented a new, original, and ornamental Design for an Ash Tray, of which the following is a specification, reference being had to the accompanying drawing, forming a part thereof.

The other side of the ash tray is a substantial duplicate of the side shown.

I claim:

The ornamental design for an ash tray, as shown and described.

ADOLPH SCHERTZ.
